[57] CLAIM

The ornamental design for a pants hanger, as shown.

DESCRIPTION

FIG. 1 is a perspective view of a pants hanger showing my new design;

FIG. 2 is a front elevational view thereof;

FIG. 3 is a side elevational view thereof;

FIG. 4 is a top plan view thereof; and

FIG. 5 is a bottom plan view thereof; and

FIG. 6 is a perspective view showing the clamps open and the sides thereof offset relatively in a position for receiving a pair of pants.

*Fig. 1.**Fig. 2.**Fig. 3.**Fig. 4.**Fig. 5.**Fig. 6.*
